CLAIM

An ornamental design for a tool pouch, as shown and
described.

DESCRIPTION

FIG. 1 is a perspective view of a tool pouch, showing
my new design;

FIG. 2 is a right side elevational view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a perspective view of a second embodiment;

FIG. 8 is a rear elevational view thereof with a frag-

mented belt;

FIG. 9 is a right side elevational view thereof;

FIG. 10 is a front elevational view of the second em-
bodiment, showing the rear of the belt fastening ele-
ments; and,

FIG. 11 is a left side elevational view thereof with a
fragmented belt.
